UNITED STATES PATENT OFFICE.

CHARLES G. MAYER, OF HAZLETON, PENNSYLVANIA.

ROTARY MOTOR.

No. 889,944.

Specification of Letters Patent.

Patented June 9, 1908.

Application filed November 20, 1905. Serial No. 233,286.

To all whom it may concern:

Be it known that I, CHARLES G. MAYER, a citizen of the United States, and a resident of Hazleton, in the county of Luzerne and State of Pennsylvania, have invented a new and Improved Rotary Motor, of which the following is a full, clear, and exact description.

This invention relates to improvements in rotary motors, the object being to provide a motor of simple construction that may be operated with an economical use of steam or other motive agent.

Other objects of the invention will appear in the general description.

I will describe a rotary motor embodying my invention and then point out the novel features in the appended claims.

Reference is to be had to the accompanying drawings forming a part of this specification, in which similar characters of reference indicate corresponding parts in all the figures.

Figure 1 is an elevation partly in section, with a portion broken away, of a rotary motor embodying my invention; Fig. 2 is a section on the line 2—2 of Fig. 3, the piston drum being omitted; Fig. 3 is a transverse section; Fig. 4 is a section on the line 4—4 of Fig. 1; Fig. 5 is a diagrammatic view showing the course of the motive agent; Fig. 6 is a sectional elevation showing a modification; Fig. 7 is a fragmentary section on the line 7—7 of Fig. 6; and Fig 8 is a diagrammatic view illustrating the course of the motive agent.

Referring to the drawings, 10 designates a cylinder having heads 11, which as here shown, are convexed at the inner side; this construction however, is not essential to the invention.

Extended through the cylinder heads and having bearings therein is a shaft 12 on which the piston drum 13 is mounted. The piston drum is divided into a plurality of chambers by annular flanges 14, and extended from the flanges in each chamber are blades 15, and alternating with the pairs of blades 15 are center blades 16, the length of these center blades 16 being approximately equal to the space between opposite blades 15.

Arranged in the lower portion of the cylinder 10 are ports 17, which as clearly shown in Fig. 2 have a spiral trend so that steam or other motive agent entering one chamber will operate against the blades therein and

thence pass to the next chamber, and so on to the end. The motive agent enters the first one of the ports through an inlet port 18, and the exhaust takes place through the port 19. The said inlet port has an inlet chamber and a restricted outlet, so that the steam is compressed as it enters the cylinder, adding materially to the force upon the piston.

By reference to Fig. 5 it will be seen that the motive agent passes practically in a zig-zag course through the chamber, filling the space between the blades and impinging against the annular flanges.

In the example of my improvement shown in Fig. 6, the port arrangements in the cylinder are the same as that first described, and the piston drum 13 is similar to the first drum, inasmuch as it is divided into a plurality of chambers by the annular flanges 14. In this instance however, the blades 20 extend entirely across the space between flanges, thus forming end walls of pockets for receiving motive agent.

The cylinder is likewise divided into a plurality of pockets by abutment blades 21 which extend across the space between annular flanges 22. In this example the steam or other motive agent enters and passes in a zig-zag course over the several blades, the fixed blades 20 forming abutments so that the expansive pressure is on the blades carried by the piston drum, and this is clearly illustrated in the diagrammatic view, Fig. 8.

While I have indicated the ports 18 and 19 as inlet and exhaust ports, it is obvious that the piston may be reversed by permitting the steam to enter the port 19 and pass out through the port 18.

It will be noted that the several chambers, the side walls of which are formed by the flanges 14, are all of equal area, so that the expansive force of the steam is at all times in a forward direction and therefore without loss of energy from lateral expansion, as resulting when the chambers gradually increase in area or width from the inlet to the outlet.

Having thus described my invention, I claim as new and desire to secure by Letters Patent:

1. A rotary motor, comprising a casing provided in its wall with a spiral port having an enlarged inlet chamber and a contracted outlet, and a piston drum mounted to revolve in the casing, said drum being provided on its periphery with a series of annular flanges forming with the casing a plu-

22
rality of annular chambers, pairs of blades on the flanges opposite each other, and blades on the periphery of the drum between the pairs of blades and of a length approximately equal to the distance between the opposing ends of the said pairs of blades.

2. A rotary motor, comprising a casing provided in its wall with a spiral port having an enlarged inlet chamber and a contracted outlet, and a piston drum, mounted in the casing and provided on its periphery with annular flanges forming with the casing a plurality of chambers, and blades so arranged

in the chambers as to cause a tangential or zig-zag passing of the motive agent through the chambers, the division wall of the spiral port being approximately opposite the center of the said chambers.

15 In testimony whereof I have signed my name to this specification in the presence of 20 two subscribing witnesses.

CHARLES G. MAYER.
